G. M. Mowbray.
Fuse for Exploding Nitro Glycerine in Wells.
No 93,113. Patented July 27, 1869.

UNITED STATES PATENT OFFICE.

GEORGE M. MOWBRAY, OF TITUSVILLE, PENNSYLVANIA.

IMPROVED METHOD OF EXPLODING NITRO-GLYCERINE.

Specification forming part of Letters Patent No. 93,113, dated July 27, 1869.

To all whom it may concern:

Be it known that I, GEORGE M. MOWBRAY, of Titusville, in the county of Crawford, in the State of Pennsylvania, have invented a new and Improved Mode of Exploding Nitro-Glycerine, Dynamite, &c., and of rendering the explosion of gunpowder more efficient and complete, which invention is particularly advantageous for blasting in artesian wells, hydraulic engineering, submarine blasting, &c.; and I do hereby declare that the following is a full and exact description thereof, reference being had to the accompanying drawings, and to the letters of reference marked thereon.

The nature of my invention consists in the use of electricity to ignite one or several fuses, which then explode a similar number of fulminating charges, thereby causing the more rapid and perfect explosion of nitro-glycerine, dynamite, and other explosive compounds, which are more difficult to explode than gunpowder, vastly increasing their disruptive force, as well as the disruptive force of gunpowder, in consequence of the rapidity with which the fulminate flame and heat pervade the whole. More especially is this the case when several fuses and fulminate charges are fired by the all-but simultaneous flash of the electric spark in a bulk of explosive matter.

My invention, then, is particularly useful in explosions designed to enlarge the diameter of an artesian or petroleum well at considerable depths under water, for submarine blasting of heavy charges of gunpowder, because the compound to be fired cannot escape into the surrounding water before all its particles have been converted into gases by the intensely-heated and rapid flame of the fulminate.

The compound most difficult to explode with precision, as to the instant of explosion, and with safety, as regards the operator, is, perhaps, nitro-glycerine, for a current of electricity from two hundred cells, containing one gallon and a half each, has failed to explode it; while the results of a premature explosion are usually so terrible, that certainty of explosion at will, and without risk to the operator, has been a desideratum. This my invention secures.

To enable others skilled in the art to make and use my invention, I will proceed to describe its construction and mode of operation,

and select for this purpose the details of exploding nitro-glycerine in a petroleum-well.

Near to the well to be operated upon, I provide the means for exciting an intense current of electricity, for which purpose I prefer a frictional electric machine, with a condenser, equivalent to a Leyden Jar, attached. The Ruhmkorff or Page induction-coil will answer; but the battery, with its charge of acid to induce the current, is inconvenient to transport. Therefore I prefer a frictional electric machine, one having a plate of ebonite, or hard rubber, about ten inches diameter, is sufficient; and I find that from ten to twenty turns of the handle of such a machine, when in good order, is sufficient to give a spark between two points three-quarters of an inch apart.

I next provide a well-insulated wire, of sufficient length to lead from the discharging-knob to the point where the explosion is desired to operate. A solution of continuity in the copper conducting-wire is made at this point; and between the divided wires, whose points need not be more than one thirty-second of an inch apart, I introduce a few grains of a priming composition, to serve as a fuse, composed as follows: Sulphuret copper, nine parts; subphosphuret copper, two parts; and chlorate potash, three parts, intimately mixed and dried. This composition is effectually secured between the ends of the insulated wire, where the solution of continuity exists, so that the current of intense electricity may discharge itself through the priming composition, and, as the spark leaps from point to point, ignite it.

Close to this priming, or surrounding it, but separated therefrom by collodion, paraffine, or tinfoil varnished, I now place ten grains, or thereabout, of fulminating mercury, or its equivalent.

For exploding nitro-glycerine or dynamite in an oil-well, a cylinder, made of tin plate, three inches diameter, and about eighteen inches in length, with a wired bail or handle, and closed at bottom, is conveniently suited for holding the nitro-glycerine.

As water does not interfere with the explosion of nitro-glycerine, the mouth of the cylinder may be left open.

The bail or handle should have a wooden guard round it, like an ordinary pail-handle,

so that, when the insulated wire is hitched round it, to prevent slipping, for the purpose of lowering into the well, the insulation may not be destroyed by chafing.

Having charged the cylinder with nitro-glycerine, the quantity being determined by the amount of work to be performed, that part of the insulated wire to which the fuse and fulminate are attached is immersed below the surface-level of the nitro-glycerine, a few turns taken round the handle of the cylinder, and a hitch taken to prevent slipping. The cylinder is then lowered to the point where the explosion is desired to occur, by means of the insulated wire; the end of the return-wire *b* being so arranged as to conduct a current of electricity from its terminating-point, either to the tin cylinder or to water of the well, and thence to earth, as before described. Connection is now made between the leading-wire and the discharging-knob of the electrical machine, and next the negative pole is connected with earth or water; upon taking from ten to twenty turns of the handle of machine, sufficient electricity is induced, when the discharger is sprung to insure explosion.

Explanation of Drawing.

Figure 1 is a general view of the electrical machine, the reel for lowering the wire, and the cylinder containing the nitro-glycerine, as adapted for an artesian well.

A is the electrical machine; *B*, the reel for

the conducting-wire. *C* is the tin cylinder, containing the nitro-glycerine. *a* is the leading or conducting wire. *b* is the return-wire, leading from the machine to earth.

Fig. 2 is an enlarged view of the cylinder, with the leading-wire *a*, return-wire *b*, and fuse, with its fulminate attached, *c c*. Fig. 3 is an enlarged view of the leading-wire *a*, the return-wire *b*. Both these wires pass through an insulating-material into the priming-composition of the fuse *d*, which explodes the fulminate *f*.

I do not broadly claim, as my invention, the use of electricity in blasting, nor the use of insulated wire for the like purpose; nor do I claim the above-described priming-composition; nor do I claim fulminating mercury, or its equivalent; but

What I do claim as my invention, and desire to secure by Letters Patent, is—

An electrical fuse for discharging nitro-glycerine, composed of the priming-composition specified, or its equivalent, for inclosing the circuit-wires at their point of interruption, in combination with an intermediate priming-charge of fulminate of mercury, or its equivalent, all inclosed in cylinder *C*, and arranged substantially as and for the purpose specified.

GEO. M. MOWBRAY.
